United States Patent Office.

WENDELL WRIGHT, OF BLOOMFIELD, NEW JERSEY.

Letters Patent No. 97,980, dated December 14, 1869.

IMPROVEMENT IN REVOLVING CUPBOARD.

The Schedule referred to in these Letters Patent and making part of the same

To all whom it may concern:

Be it known that I, WENDELL WRIGHT, of Bloomfield, in the county of Essex, and State of New Jersey, have invented a new and useful Improvement in Revolving Cupboards; and I do hereby declare that the following is a full, clear, and exact description thereof, which will enable others skilled in the art to make and use the same, reference being had to the accompanying drawings, forming part of this specification.

The object of this invention is to form a communication between two adjoining rooms, through the intervening partition, to utilize space in a corner or angle of a room; and

The invention consists of an outer casing, (circular or otherwise,) in one or more sections, and a series of circular shelves divided by upright rings, and supported by central pivots on which the shelves and rings revolve, as hereinafter more fully described.

In the accompanying drawing—

Figure 1 represents a horizontal section of the cupboard, through the line x x of fig. 2.

Figure 2 is a vertical section of the cupboard, through the line y y of fig. 1.

Similar letters of reference indicate corresponding parts.

This cupboard may be made of any desired length and diameter, and may extend to the floor or not, as may be desired, and have any desired number of shelves and wings.

A represents the partition between two apartments. B is the casing, which may be made circular, (as represented,) or in any other form. It may be made in sections, with a door on each side of the partition, for giving access to the cupboard, as seen in the drawing. When the cupboard is placed in a corner or angle, the casing would be in one section, while the shelves would revolve as represented.

C represents the doors.

D represents the shelves of the revolving cupboard. These shelves are divided by the upright wings E.

E is the top of the cupboard, and G is the bottom.

The revolving cupboard may extend to the bottom of the casing A, if desired, or a recess, H, on each side of the partition, may be left beneath it, as seen.

I I represent pivots, on which the cupboard revolves. To place the cupboard properly in the partition, an aperture of the size of the casing A is cut through.

The casing is secured in the aperture thus made at the sides, or at the bottom or top, either permanently or otherwise.

J J represent the hinges of the doors.

A door being on each side or section of the casing, it will be seen that a communication is opened between two adjoining rooms or apartments without the possibility of seeing from one to the other.

Articles, as books, crockery, or clothing contained in any of the compartments of the cupboard are readily obtained in either room. Where a kitchen adjoins a dining-room, dishes may be readily transferred from one room to the other without opening a door. Many other advantages will readily suggest themselves to all who examine the subject.

I am aware that revolving closets are old, and not of my invention; but

What I esteem to be new in my application, and desire to secure by Letters Patent, is—

The arrangement of a revolving closet within a stationary chamber that opens into two adjoining rooms, as and for the purpose specified and shown.

WENDELL WRIGHT.
